UNITED STATES PATENT OFFICE.

JOHN HENRY BELL, OF LAWRENCE, KANSAS.

PIANO.

SPECIFICATION forming part of Letters Patent No. 637,069, dated November 14, 1899.

Application filed March 8, 1899. Serial No. 707,597. (No model.)

To all whom it may concern:

Be it known that I, JOHN HENRY BELL, a citizen of the United States, residing at Lawrence, county of Douglas, and State of Kansas, 5 have made certain new and useful Improvements in Pianos, of which the following is a specification.

My invention is an improvement in pianos, and has for an object to provide a spring between some two parts of the action whereby to produce a perceptible yielding action in transmitting the motion from the key to the hammer.

The invention consists in certain novel constructions and combinations of parts, as will be hereinafter described, and pointed out in the claims.

In the drawings, Figure 1 is a sectional side view of part of an action, showing the spring applied to the key-rocker. Fig. 1^a is a side view of the rocker having an integral spring. Fig. 1^b is a side view showing a jack-rocker arranged to receive the contact of the spring. Fig. 1^c is a side view showing the grand-support arranged to receive the contact of the spring on the key-rocker. Fig. 2 is a side view showing the spring supported on the key and having a capstan-screw for transmitting the motion to the extension. Fig. 2^a is 25 a side view of a key provided with the spring and having the key-rocker mounted on the spring. Fig. 2^b is a side view of a key provided with the spring and having the jack mounted on said spring. Fig. 3 is a side view 30 of a part of an action, showing the spring formed on or secured to the jack-rocker. Fig. 3^a is a side view showing a somewhat different form of key-rocker from that shown in Fig. 1. Fig. 4 is a side view of a part of an 35 action, showing a different form of jack-rocker from that shown in Fig. 3 and showing the jack-rocker provided with the separate spring, Fig. 5 is a side view of a part of an action, showing the jack-rocker formed with the integral spring. Fig. 6 is a side view of a part 40 of a grand-pianoforte action, showing the grand-support as formed with an integral spring. Fig. 7 shows a different form of grand-action, known as the "Brown" grand action, 45 with the spring-underhammer formed with an integral spring; and Fig. 8 is a side view 50 of a portion of an action, showing the spring

as applied to the key and bearing against the capstan-screw.

Heretofore the only yielding in a piano-forte-action under pressure of the performer's fingers has been due to a slight condensation which takes place in the felt, leather, or cloth cushions used at points of contact between the different parts or members of the action. 55 These cushions do not yield enough even when new to give to an action sufficient pliability, and when worn by use they become hard and unyielding. To avoid this objection, I introduce into the construction of a pianoforte-action a spring, which may be made of metal or wood or both metal and wood, or, if desired, of other suitable material, which is fastened to or made in and a part of some member of the action between the keyboard and the 60 hammer and is interposed between two members, which interposed spring will yield perceptibly before transmitting motion or force from one member to the next. This interposed spring is advantageous and important 65 because it improves the touch by making the action more pliable under pressure of the performer's fingers. It increases the durability 70 of the instrument by preventing the severe sudden shock which many parts are compelled to bear in the use of the old construction, and it improves the quality of the tone, because in the use of the spring the hammer is moved against the string by a throw instead 75 of a sudden knock.

My invention in its broad aspect contemplates a spring which is interposed between any two parts of the action and operates to transmit the motion from one of such parts to the other, and it should be understood that 80 I regard the key as a part of the action and will so treat it in the following description and claims.

In the drawings I have represented the spring as applied to or formed in various 85 parts of different styles of action; but I do not desire to be limited even to the scope of the invention as illustrated in said drawings, because in modifying the styles and constructions of the actions the construction and arrangement of the spring may be modified 90 to suit.

In the construction shown in Fig. 1 the key A may be of the usual construction, and the

key-rocker B is shown as provided with the spring-plate C, which is secured at one end to the key-rocker and has its projecting end arranged to transmit motion to the extension 5 C', a cushion C² being provided to form a seat for the free end of the spring when the latter is flexed.

In Fig. 1^a the key-rocker B' has the integral spring-arm b' and a cushion b² therefor.

10 In Fig. 1^b the key-rocker is the same as in Fig. 1, as is also its spring C and cushion C²; but instead of the extension C', I provide the jack-rocker C³ to receive the action of the spring-arm C.

15 In Fig. 1^c the key-rocker is the same as in Fig. 1, and I also transmit action from the spring thereof, such action being exerted in said Fig. 1^c against the grand-support C⁴.

In Figs. 2, 2^a, and 2^b the spring is secured 20 to the key A', and such spring A² has at its free end a block A³, which seats against the cushion a³. In Fig. 2 the block A³ has a capstan-screw A⁴, which bears against the extension A⁵. In Fig. 2^a a key-rocker A⁶ is mounted on the block 25 A³ and transmits motion to the extension A⁷, while in Fig. 2^b the jack A⁸ is mounted on the block A³.

Referring now to Fig. 3, it will be seen that the spring D is a plate secured to the jack-rocker D' and is arranged for contact by the extension D².

In Fig. 3^a I show a different form of key-rocker D³ from that shown in Fig. 1.

In Fig. 4 the spring E is secured to the 35 jack-rocker E' in position for contact by the capstan-screw E².

In Fig. 5 the spring is made integral with the jack-rocker by slotting the same, and a felt cushion e forms a seat for such spring.

40 In Fig. 6 I show the grand-support F as slotted to form the spring and as arranged for contact by the capstan-screw F'.

In Fig. 7 the spring is formed by slotting the spring under hammer at G, the cushion 45 g being provided, as shown.

In Fig. 8 the spring-plate H is secured to the key and transmits motion to the capstan-screw H'.

It will be noticed that throughout the several views felt or similar cushions are provided to form seats for the spring when the latter is bent under stress of operation.

It will be understood that I have illustrated my improvement as applied to the various 55 styles of action. Thus in Fig. 1 I show a portion of a grand or upright pianoforte action, in Fig. 1^a a part of an upright action, in Fig. 1^c a part of a grand action, in Fig. 2 a part of a grand or upright action, in Fig. 2^a a part of

60 a grand or upright action, in Fig. 2^b a part of a Brown grand-pianoforte action, in Fig. 3 a part of an upright action, in Fig. 4 a part of an upright action, in Fig. 5 a part of an upright action, in Fig. 6 a part of a grand action, in Fig. 7 a part of a Brown grand action, and in Fig. 8 a part of a grand or upright action.

Fig. 3^a shows a key-rocker which in itself is no part of the invention, but is shown to illustrate a form which is used on the key of a grand or upright action instead of the extension or the capstan-screw, in which case the jack-rocker, Fig. 3 or Fig. 4 or Fig. 5, or the grand-support with spring attached (in a similar manner to Fig. 3 or Fig. 4) or with integral spring, Fig. 6, rests upon said key-rocker.

Having thus described my invention, what I claim, and desire to secure by Letters Patent, is—

1. A piano-action having one of its parts 80 provided with a separate spring-plate secured at one end to such part and arranged at its free end to form a yielding contact between such part and an adjacent one, substantially as set forth.

2. A piano-action having a resilient portion for transmitting the key motion to the hammer, such portion yielding perceptibly in the direction of the transmission of the motion in transmitting such motion whereby to render 90 the action pliable substantially as set forth.

3. A piano-action having a spring plate or arm for transmitting the key motion to the hammer, such plate or arm being extended in a direction approximately at a right angle 95 to the direction of the transmission of the motion and yielding perceptibly in such direction in transmitting the motion substantially as set forth.

4. A piano-action having an interposed 100 spring for transmitting motion between two adjacent parts, such spring yielding perceptibly in the direction of such movement whereby to render the action pliable substantially as set forth.

5. A piano-action having one of its parts provided with a spring for transmitting the key motion, such spring being arranged to yield perceptibly in the direction of such motion, and a cushion forming a seat for such 110 spring substantially as set forth.

6. A piano-action having one of its parts provided with a spring plate or arm for transmitting the key motion, such plate or arm being fixed at one end and yielding perceptibly 115 at its free end in the direction of the transmitted motion substantially as set forth.

7. In a piano-action the combination of the key and the key-rocker mounted thereon and provided with a spring plate or arm for transmitting the key motion, fixed at one end with relation to the rocker, extended approximately parallel with the key, and yielding at its free end in a direction at right angles to the direction of the transmitted motion, substantially as set forth.

8. A piano-action having a spring-plate arranged to transmit the key motion to the hammer, such plate being extended transversely of the direction of the transmitted motion and arranged to yield perceptibly in the direction of such movement substantially as set forth.

9. A piano-action having a resilient portion for transmitting the key motion to the ham-

mer, such portion being arranged to yield perceptibly in transmitting the motion, substantially as set forth.

10. A piano-action having in combination with the hammer and connecting parts a spring-arm for transmitting the stroke movement to the hammer, such arm being fixed at

one end and arranged to yieldingly transmit motion to the hammer, substantially as set forth.
